UNITED STATES PATENT OFFICE.

GEORGE F. PULLEN, OF WATERBURY, CONNECTICUT, ASSIGNOR TO LANE MANUFACTURING COMPANY, OF WATERBURY, CONNECTICUT, A CORPORATION OF CONNECTICUT.

FASTENER ASSEMBLING AND ATTACHING MEANS.

1,178,679.

Specification of Letters Patent. Patented Apr. 11, 1916.

Application filed October 25, 1913. Serial No. 797,179.

To all whom it may concern:

Be it known that I, GEORGE F. PULLEN, a citizen of the United States, residing at Waterbury, in the county of New Haven, in the State of Connecticut, have invented certain new and useful Improvements in Fastener Assembling and Attaching Means, of which the following is a specification.

My invention relates generally to new and useful improvements in machines for assembling parts of garment or other fasteners which comprise a plurality of parts which are brought together in a fixed relation to constitute a completed fastener or a member thereof.

The invention consists in the improved construction to be more fully described hereinafter and the novelty of which will be particularly pointed out and distinctly claimed.

I have fully and clearly illustrated my invention in the accompanying drawings to be taken as a part of this specification and wherein—
Figure 1 is a view in front elevation of a structure embodying my present invention. Fig. 2 is a vertical central section on the line 2—2 of Fig. 1. Fig. 3 is a horizontal section on the line 3—3 of Fig. 2. Fig. 4 is a semi-diagrammatic view, partly in section, of a portion of one of the feed guides showing a cut-off and feed-plunger in one position. Fig. 5 is a similar view to Fig. 4 showing the cut-off and plunger in another position. Fig. 6 is a view in side elevation with parts broken away, and in section, of one of the drums for containing the fastener parts. Fig. 7 is an enlarged vertical central sectional view through the dies for assembling the fastener parts. Fig. 8 is a detail sectional view of parts of one type of fastener upon which the machine is designed to operate; and, Fig. 9 is a central vertical sectional view through the parts shown in Fig. 8 after the same have been assembled.

Before entering into a description of my invention I will describe briefly one well-known type of fastener or fastener element upon which it may operate as shown in Figs. 8 and 9. In these figures the fastener comprises a resilient head *a* in which is inserted an anvil piece or socket *b* having an anvil projection *c*, and a hollow neck *d*, said head and anvil socket having engaging flanges *e*, *f*, respectively, at the lower ends, which

flanges are secured together by an annular collar *g*, all substantially as shown. *h* designates a shank or stem member consisting of a shank *h'* and flange *i*, said shank or stem being intended to pierce through a fabric and be passed within the hollow neck *d*, the head and stem member being clamped together by forcibly thrusting the end of the shank *h'* into engagement with the anvil *c* which serves to spread and distend the metal of the shank *h'* into substantially the position shown in Fig. 9. When the parts are united the fabric to which the fastener is attached is securely clamped between the flange piece of the head member and the flange of the shank member.

I will now describe one type of machine in connection with which my invention is employed, said machine forming no part of my present invention except in so far as it, or parts thereof, may enter into combination therewith, said machine being the invention of John Draher and covered by Letters Patent No. 1,165,078, of December 21, 1915.

Referring now more particularly to Figs. 1, 2 and 3 of the drawings, *A* designates generally a frame which consists of a base plate 1 and a vertical post or standard 2 having a forwardly-extending overhanging arm 3 provided with a vertical guide passage or bore 4. Cast integral with the forward part of the base is a projection 5 having a vertical opening 5^a therein aligning with the opening 4. Arranged to slide in the opening 4 is a plunger 6 carrying a die member 7 formed with an opening 8 at its lower end and an impact surface 9 at the bottom of said opening, and designed to coöperate with the socket member in assembling the same with a stud member held by an opposing die 10 supported by the forwardly-projecting part 5. At the head of the column 2, are vertical parallel ears 11 in which is seated a bearing pin 12, upon which is fulcrumed at a point intermediate its ends, an operating lever 13, consisting of a substantially vertical portion 14 extending in rear of the frame or stand, and a forwardly-extending overhanging portion 15 connected to the head of the plunger 6 by a link connection 16 whereby said plunger 6 may be reciprocated. The downward movement of the lever 13 may be limited by a stop screw 17 threaded into the arm 3 beneath the portion 15 of said lever. The lower end of the lever 110

13 carries a suitable connection 13^a by means of which said lever may be connected to a foot treadle or power mechanism (not shown) for swinging said lever on its fulcrum.

5 The construction of the dies is not important as far as my invention is concerned, so I will not describe the same with detail here.

10 When the member 7 is forced down by the operating lever 13, it moves the head or socket part of the fastener down onto the stud member supported on the die 10, serving to expand the stud member to lock the 15 same to the socket member. The die 7 contains a holding spring 7^a to hold the head of the socket member in moving the latter down toward the stud member.

Supported on the base 1 are upper and 20 lower horizontal guide ways, 18, 19, respectively, provided, respectively, on their upper surfaces with longitudinal grooves 20, 21, leading forward to the space between the dies 7 and 10, to deliver the head and 25 stud parts to the dies with the head part above the stud part. Arranged in each of the grooves 20, 21, respectively, and reciprocable lengthwise thereof, in the said ways are plunger blades 22, 23, carried by plunger bars 24, 25, respectively, sliding in upper and lower horizontal guide openings 26, 27, in the vertical post 2, the rear ends of said plunger bars 24 and 25 being connected by links, 28, 29, to the depending portion 14 30 of the operating lever, the arrangement being such that when the said lever is swung toward the post 2 the plunger 6, and its die 7 will be raised while the blades 22, 23, will be moved forward to move to the dies fastener parts which may have been deposited 35 in said slots 20, 21 by supply and feed means to be presently described.

Supported on the upper portion of the post 2 is a horizontally disposed shaft 30, 40 supporting on each of its ends a fixed non-rotatable plate 31, secured to said shaft by a set-screw 32, and having on its inner face an annular flange 33. Also mounted on the shaft between said arm 3 and each of the 45 plates 31 is a rotatable drum 34 consisting of a head having an annular flange 35 to coöperate with the aforesaid flange 33, each drum thereby forming with its adjacent plate a receptacle for the fastener parts 50 to be assembled. The flange 35 of each drum is formed with a plurality of tangential slots 37 of a width slightly greater than the neck of the shank portion, or the head of the socket portion of the fastener parts. 55 Connected to the lower forward end of each of said plates 31 is a feed chute 39, one of which leads to the guide way 18 and the other to the guide way 19, the lower end of each of said chutes opening into the side of 60 the guide way into which it delivers the

parts. Each of these chutes consists of a plate or strip of metal curved downward and inward toward the way it supplies, and is formed on its inner face with a longitudinal groove 40 down which the fastener 70 parts gravitate, said parts being held in the groove by side strips 41, 41, secured to the grooved face of the chutes. The said strips 41, 41, at their inner edges overhang the groove 40, so that the edges 75 of the flanges of the fastener parts pass beneath the overhanging parts of said strips, and the shanks or heads pass between the adjacent edges of said strips. About the inner face of each plate 31 is a strip 42 80 forming a continuation of one of the strips 41, and a small section 43, forming a continuation of the other strip 41. The flange of each drum and the slots therein are so arranged with reference to the inlet end 44 85 of the guide channel in the chute that the fastener parts may pass therethrough, the flange of each of the drums being spaced from the circular portion of the plate 31 sufficiently to permit the flanges of the fastener parts to pass between the said flange and said plate and be delivered into the 90 guide channel of the feed chute. Each of the plates 31 is provided with an inlet hopper 45 through which the parts are supplied to the drum, and is also provided with an opening 46 closed by a threaded plug 47 through which the drum may be emptied of its contents.

Mounted on the inner face of each of the 100 drums 34, fixed thereto, and surrounding the shaft 30, is a ratchet wheel 48 with which coöperates a pawl 49 pivoted as at 50, on a pawl carrier 51 fulcrumed on the shaft 30 and having a segmental rack 52 105 on its forward portion. Fulcrumed on the forward part of the head 3, as at 53 and on opposite sides of the latter are levers 54 having at their free ends segmental racks 55 which mesh with the segmental racks on the 110 pawl carriers. Connecting each of the levers 54 with the overhanging part 15 of the operating lever is a link 57, whereby said levers 54 are pulled upward at the same time as the plunger 6, and the pawl carriers 115 are thrown to cause the pawls to engage the ratchet wheels and revolve the drums. The pawls are yieldingly held in engagement with the ratchet wheels by springs 56 so that when the levers are moved downward, the pawls ride over the ratchets. 120

The outer end of the upper way 18 terminates just short of the plunger 6, and at the end of said way is provided means to receive a fastener part when it is thrust forward by the blade 22, and support it in the path of movement of said plunger to be moved by the latter toward the lower die. This means comprises two blocks 57, supported on opposite sides of the plunger and 130

aving semi-circular recesses 58, fitting about said plunger, said blocks being each supported by a leaf spring 59, secured at one end to the head 3, said springs serving to yieldingly hold the blocks in engagement with the plunger. At the side toward the end of the upper guide way, the blocks 57 are each provided with a recess 60 located above a shoulder 61, said recesses being adapted to form a passageway to receive the fastener parts, and leading to an annular seat 62 formed by inner semi-circular recesses in said blocks into which the fastener part is thrust by the finger 22 through the passageway formed by the recesses 58.

The mechanism so far described, constitutes the invention of John Draher, as above stated, except in so far as it may enter into combination with the mechanism I will now describe exemplifying an embodiment of my invention.

The strips 41, 41 which overlie the grooves in the chutes 40 are respectively formed one with a recess 63 and the other with a projection 64 directed toward said recess, the arrangement being such that the passage between said strips is provided with a lateral offset or deflection 65 providing a resting or supporting ledge or shoulder to catch and support the lower one of a column of the fastener parts as said parts descend the chute. Working in a transverse slot 66 in each of the chutes, and reciprocable lengthwise of the offset 65 is a thrust member 67 which serves to push the fastener supported on said ledge 65 out into the inclined portion 68 of the guide slot so that the fastener part may gravitate into the way to which the chute is connected. It will be seen that this projection 64 and the lateral offset or deflection 65 are located at a point intermediate the ends of the chute, so that the parts may be fed into the lower portion of the chute one at a time and gravitate down the same freely without hindrance or jamming. This is an important advance over those feed devices in which an uninterrupted column of fasteners extends the full length of the chute, in which case the parts are liable to jam and interfere with the successful operation of the machine. The inclined portion 68 of the slot is formed by one of the walls of the recess 63, and the lower inclined edge of the projection 64.

The thrust member 67 is connected to a slide member 69 slidable in a slot 70 beneath the strips 41, 41, said slide member being movable transversely of the chute, and said slide members being each pivoted as at 71 to one end of a link 72, one end of one of said links being pivoted to a rocking lever 73 fulcrumed at its lower end on a rock shaft 74 having bearing in the base of the post. The upper end of the lever 73 is

pivoted as at 75 to one end of a connecting link 76, the opposite end of which is pivoted as at 77 to the lever 13 below the fulcrum thereof. The opposite end of the rock shaft 74 carries a lever 78 to which is connected the link 72 on the opposite side of the machine for the slide member 69 for the opposite chute.

Carried by each of the slide members 69 is a finger 79 preferably overlying the chutes and adapted to pass between the lowermost fastener part and the next adjacent part when the former is pushed from the ledge 65 by the push member into the inclined portion of the chute-way. The inner ends of the fingers 79 and the push members 67 are so proportioned and arranged with relation to each other, that when one is withdrawn from the path of descent of the parts, the other is projected into position to support the column of parts. The said finger 79 and push member 67 of each set are also spaced apart such a distance one above the other that the column of fasteners supported by the said finger, is supported above and out of contact with the fastener part resting on the ledge 65, so that the said part is free of the weight of the column and can, therefore, be easily pushed off the said ledge by the push member 67. It will be apparent that the members 67 and 79 operate together as a cut-off to separate the lowermost fastener part from the column of such parts, and deliver the same to the means for presenting the parts to the dies, and at the same time supporting and retaining the remainder of the column against descent of the chute. In order to provide for the desired spacing between each finger 79 and the push member 67 associated therewith, I preferably pivot each finger on its slide member 69, by means of a clamping screw 69^a so that the said finger may be adjusted toward and away from the push member. The upper inner edge of the member 67 may be cut away or recessed as at 67^a so, that when the members 67 and 79 are moved from the position shown in Fig. 4 to the position shown in Fig. 5, the lowermost part supported on the upper edge of the finger 79, will drop into said recess so as to be in proper position to pass between the finger and the push member when the latter are moved from the position shown in Fig. 5 to that shown in Fig. 4.

The parts being constructed as above described the operation of the machine is as follows: Assuming that the parts are in the position shown in Fig. 2, with the die 7 at the limit of its downward position, and a socket or head piece being in the groove of the guide way 20, and a stud in the groove of the guide way 21, the lever 13 is moved to the left or toward the standard 2 from

the position shown in Fig. 2, whereupon the plunger 6 is raised and the blades 22, 23 move forward to push the fastener parts respectively into the seat in the blocks 59, 5 and to the die 10. During this movement the push or thrust members 67 move forward from the position shown in Fig. 5 to the position shown in Fig. 4, to permit the lowermost part in each chute to gravitate 10 onto the ledges 65, the fingers 79, being projected across the slots of the chutes beneath the next lowermost part to support the columns of parts. At the same time the levers 54 are raised to swing the pawl carriers downward to rotate the drums 34. The movement of the operating lever 13 is then reversed, whereupon the plunger 6 is moved downward, spreading the blocks 57 apart and the die 7 carrying the head part of the 20 fastener down, and impressing it over the stud part supported on the die 10 to thereby clench said parts together. During this operation the blades 22 and 23 are moved to the position shown in Fig. 5 so as to uncover 25 the entrance from the chutes into the guideways 18, 19, and the thrust members 67 push the fastener parts from the ledges 65, down into the lower portions of the chutes whence the said parts gravitate singly to the grooves 30 of the guide ways 22, 23 as shown in Figs. 2 and 5, in position to be pushed to the dies by the blades 22, 23, when the operating lever is next operated in the opposite direction from that just described. When the 35 lever 13 is moved to the rear, the levers 54 are raised to pull the pawls 49 back into position to engage the ratchet wheels 48 to rotate the drums when the lever 13 is again moved forward, as above described.

40 What I claim and desire to secure by Letters Patent of the United States is:—

1. In a machine of the character set forth, a guide chute for fastener parts having a groove for passage of said parts, a ledge intermediate the ends of said groove for supporting a fastener part, a member movable transversely of said groove, a push member carried by said first-named member, to push a fastener part from said ledge, and a finger

carried by said first-named member and 50 located above the push member to support a column of fastener parts, said finger being supported on an adjustable pivot.

2. In a machine of the character set forth, a guide chute for fastener parts having a 55 groove for passage of said parts, a ledge intermediate the ends of said groove for supporting a fastener part, a member movable transversely of said groove, a push member carried by said first-named member, to push 60 a fastener part from said ledge, and a finger carried by said first-named member and located above the push member to support a column of fastener parts, said finger being adjustable toward and away from said push 65 member.

3. In a machine of the class described, in combination, upper and lower guideways, means to move a fastener part lengthwise of each guideway, guide chutes for parts discharging into said guideways, means for supporting a column of parts in each guide chute, means for delivering the lowermost part from each guide chute to said guideways, and means for supporting the parts 75 above the one delivered.

4. In a machine of the character described, superposed guideways, plungers in said guideways to position fastener parts, guide chutes leading to said guideways, a 80 ledge intermediate the ends of said guide chutes adapted to support a fastener part, a push member movable in one direction to dislodge a fastener part from said ledge, a finger to support the fastener parts when 85 the push member is moved in the opposite direction, an operating lever and connections between the plungers and said push members and fingers whereby the fastener parts are dislodged when said plungers are 90 in a retracted position.

In testimony whereof I have hereunto signed my name in the presence of two subscribing witnesses.

GEORGE F. PULLEN.
